(57) **CLAIM**

The ornamental design for a magnetic fastener, as shown and described.

DESCRIPTION

FIG. 1 is a top perspective view of a magnetic fastener showing my design;

FIG. 2 is top perspective view of the magnetic fastener of FIG. 1, shown with the magnetic fastener in separated form; FIG. 3 is a bottom perspective view of the magnetic fastener of FIG. 1;

FIG. 4 is a bottom perspective view of the magnetic fastener of FIG. 1, shown with the magnetic fastener in separated form;

FIG. 5 is front elevational view of the magnetic fastener of FIG. 1;

FIG. 6 is a rear elevational view of the magnetic fastener of FIG. 1;

FIG. 7 is a left side elevational view of the magnetic fastener of FIG. 1;

FIG. 8 is a right side elevational view of the magnetic fastener of FIG. 1;

FIG. 9 is a top plan view of the magnetic fastener of FIG. 1; and,

FIG. 10 is bottom plan view of the magnetic fastener of FIG. 1.

The portions shown in broken line do not form part of the claimed design.
